UNITED STATES PATENT OFFICE.

TRACY L. PAINE, OF MILWAUKEE, WISCONSIN.

TOKEN-HOLDER.

1,117,598.

Specification of Letters Patent. Patented Nov. 17, 1914.

Application filed December 30, 1912. Serial No. 739,264.

To all whom it may concern:

Be it known that I, TRACY L. PAINE, a citizen of the United States, and resident of Milwaukee, in the county of Milwaukee and State of Wisconsin, have invented certain new and useful Improvements in Token-Holders; and I do hereby declare that the following is a full, clear, and exact description thereof.

10 My invention has for its object as a new article of manufacture a gravity controlled token-holder, the arrangement and construction being such that the base of the tray, from a central point, is concavo-convexed in 15 opposite directions and flat in cross-section, the said base being provided with a conical weighted stem for the support of a flat tray, which tray extends from the stem in opposite directions, paralleling the curvature of 20 the base and is provided with upturned side flanges. By this construction pressure upon the tip at the end of either of the curved portions of the base will cause the tray to tilt in a corresponding direction. Thus the 25 tray is capable of tilting in opposite directions at the convenience of the operator.

With the above objects in view the invention consists in certain peculiarities of construction and combination of parts as hereinafter set forth with reference to the accompanying drawing and subsequently claimed.

In the drawings Figure 1 represents a side elevation of a tray embodying the features 35 of my invention with parts broken away and in section to more clearly illustrate details of construction, and Fig. 2, a plan view of the same.

Referring by characters to the drawing 40 the base is formed by a transversely flat strip, which strip is concavo-convexed longitudinally and in opposite directions from its central point to form oppositely disposed curved rockers 1", the said rockers terminating with downturned engaging lips or shoulders 1'''.

Projecting upwardly from the central portion of the base is a conical hollow stem 4, which stem incases a weight 3 at its bottom, 50 the said weight being in engagement with the base, whereby the preponderance of said weight is at the bottom of the stem or point of intersection of the rocking base.

By the above described arrangement of 55 weight it is apparent that the vibratory tendency of the tray is reduced to a mini-

mum and said tray will thus quickly return to its horizontal position in response to the weight after being tilted. This arrangement of weight at the base of the stem will thus 60 absorb the vibratory shock resulting in rocking to normal position, which shock is apparently manifest to an exaggerated degree in instances where the stem is solid, in which case the weight extends through its entire 65 length and the efficiency of the bottom portion thereof is materially reduced as a means for returning the tray to its normal position, the lower portion of the solid weight stem being counteracted or neutralized by 70 the upper portion of said stem. The head of the stem carries a flat tray 5, which tray extends in opposite directions corresponding to the rockers having discharge mouths directly over said rockers. The side edges 75 of the tray 5 are upturned to form guide flanges 5' whereby coins may be directed to either discharge mouth.

In the operation of the device, when it is desired to obtain one or more coins, which 80 have been deposited upon the tray 5, the operator inserts one edge of the open hand between the tray and engaging shoulder 1''' and by a slight downward pressure the 85 holder is caused to rock, whereby the tray will tilt in toward the palm of the hand and thus discharge coins thereon into said palm. It is apparent that as soon as the pressure of the hand is relieved from the engaging shoulder that the holder will return to its 90 normal upright position, due to the gravity control effected by the weight 3 with which its base is provided, the weight being centrally disposed.

This device is designed particularly as a 95 change-making machine to be placed upon the counters of banks or stores of all descriptions for vending articles, wherein change is to be made. Heretofore it has been found that great difficulty results from customers attempting to obtain change from 100 mats of various descriptions or trays with bare or gloved hands and it frequently becomes necessary to use both hands in obtaining change from such articles. With my device this is entirely overcome as a simple hand movement, requiring no dexterity, will 105 automatically discharge the coins into the palm. Furthermore the coins or paper certificates when placed upon this tray will be 110 kept in a more sanitary manner due to the fact that they are not moistened by contact

with wet counters, tables or the like. The device being portable, is thus capable of being moved from place to place and will at all times maintain its upright position except when positively tilted.

5 I claim:

10 A new article of manufacture comprising a token-holder having a base provided with concavo-convex portions extending from a central point, the base being flat transversely, a hollow stem extending from the central portion of said base, an incased weight in connection with the bottom of the stem so arranged to present the preponderance of said weight at a point of intersection

20 between the base and stem, a flat tray supported upon the upper end of the stem the same being extended in opposite directions therefrom and in parallel relation to the curved portions of the aforesaid base, and longitudinal guide-flanges projecting from the sides of the tray.

25 In testimony that I claim the foregoing I have hereunto set my hand at Milwaukee in the county of Milwaukee and State of Wisconsin in the presence of two witnesses.

TRACY L. PAINE.
